US0D1070055S

(12) **United States Design Patent** (10) **Patent No.:** **US D1,070,055 S**
(45) **Date of Patent:** **** Apr. 8, 2025**

(54) **NECK FAN**

(71) Applicant: **Guangdong Aoyun Technology Co., Ltd.**, Guangdong (CN)

(72) Inventor: **Xueping Zhu**, Guangdong (CN)

(73) Assignee: **Guangdong Aoyun Technology Co., Ltd.**, Guangdong (CN)

(**) Term: **15 Years**

(21) Appl. No.: **29/981,527**

(22) Filed: **Dec. 31, 2024**

(30) **Foreign Application Priority Data**

Dec. 23, 2024 (CN) 202430817244.3

(51) **LOC (15) Cl.** **23-04**

(57) **CLAIM**

The ornamental design for a neck fan as shown and described.

DESCRIPTION

FIG. 1 is a front, left and top perspective view of a neck fan, showing my new design.

FIG. 2 is a rear, right and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof; and,

FIG. 8 is a bottom plan view thereof.

The dashed broken lines depict portions of the neck fan that form no part of the claimed design.

1 Claim, 8 Drawing Sheets
